UNITED STATES PATENT OFFICE.

CHARLES M. DEICKE, OF BALTIMORE, MARYLAND.

SCREEN-DOOR ATTACHMENT.

1,221,700.

Specification of Letters Patent.

Patented Apr. 3, 1917.

Application filed August 23, 1916. Serial No. 116,409.

To all whom it may concern:

Be it known that I, CHARLES M. DEICKE, a citizen of the United States, and a resident of the city of Baltimore, in the State 5 of Maryland, have invented a certain new and useful Improvement in Screen-Door Attachments, of which the following is a specification.

In my invention a "push lever" is pivoted 10 to and carried by the screen door, and it is adapted to operate the push button of the bell fixed in position on the door casing.

The lever is pivoted and supported upon a bearing, and a forked spring is secured 15 between the escutcheon plates in such manner as to act on the lever and hold it normally away from the bell push-button.

In the drawings:

Figure 1 is a partial perspective view of 20 a screen provided with my attachment, looking from the inside;

Fig. 2 is a transverse section at the level of the attachment;

Fig. 3 is a perspective view of the attachment;

Fig. 4 is a similar view of the spring, and

Fig. 5 is a front view of one of the escutcheon plates.

The invention is shown in connection with 30 a screen door 1, which, in the present instance, closes against a casing 3, and a bell having a push-button or pin 4 is arranged on the casing just inside the door. The attachment comprises a lever 5 having at each 35 end a head, one of the heads 6 having thereupon the legend "Push", and the other head 7 being plain and adapted to engage the button and press the same to actuate the bell.

The lever has a bearing 8 intermediate its 40 ends, and the said lever is adapted to be arranged within a slot 9 in the door at the level of the bell, in such manner that the head 7 will engage the button when the lever is swung in the proper direction. This 45 bearing is engaged by a supporting shaft 10 which is provided at one end with an angular pointed lug 11, and the shaft is adapted to be arranged on the inner face of the door beneath one of the escutcheon plates to be 50 described later, with the pointed lug pushed

into the material of the door and with the shaft extending transversely of the slot which is horizontal.

Two escutcheon plates are provided, the plate 12 being arranged on the inner face 55 of the door, and the plate 13 on the outer face, and the two plates are slotted as shown at 14, to register with the slot 9 of the door. The escutcheon plates have openings for receiving nails or screws 15 to secure them in 60 place.

The shaft 10 is held from disengagement with the door by the escutcheon plate 12, and a spring is provided for normally holding the lever in the full line position of Fig. 65 2. This spring 16 is a plate spring, having each end forked as indicated at 17 and 18 respectively, and the said ends are pointed obliquely to the body of the spring to lie approximately parallel with each other. The 70 fork 18 is inserted between the escutcheon plate 12 and the door with the arms of the fork on opposite sides of the holding nail for the escutcheon. The other fork 17 of the spring extends outwardly and the lever 5 75 engages between the arms of the said fork and the spring normally holds the lever in the position of Figs. 1 and 2.

When it is desired to ring the bell, the head 6 is pushed to the right, as indicated in 80 dotted lines in Fig. 2, bringing the head 7 into contact with the push button and sounding the bell. Preferably the escutcheon plate 13 is provided with the legend "Bell," as indicated at 19. With this improvement, 85 the bell arranged within the door is accessible for ringing with the door locked.

I claim:

The combination with a casing, a signal bell fixed thereon, and a swinging screen 90 door having a transverse slot, of a push lever pivoted in said slot and adapted, when the door is closed against the casing, to project horizontally over the bell, and an angular plate spring secured to the screen door 95 and its free end bearing horizontally upon the inner end of the push lever and holding it normally out of range of contact with the bell, as shown and described.

CHARLES M. DEICKE.
